UNITED STATES PATENT OFFICE

2,566,487

WATER PISTOL

John Gora and John Dale Scarbrough, Wyandotte, Mich., assignors to All-Metal Products Company, Wyandotte, Mich., a corporation of Delaware

Application May 21, 1947, Serial No. 749,526

2 Claims. (Cl. 222—79)

1

The present invention relates to toy guns, and particularly to an improved toy gun for discharging water or other liquid, the construction being such that repeated discharges from a self-contained reservoir may be induced by successive trigger actuations without reloading the gun.

An important object of the invention is to provide such a repeating water gun which is simpler to construct and assemble than previously known designs, and which although less expensive possesses a number of advantages over previously known devices of this class. An object related to that last stated is to provide such a repeating water gun incorporating a water tank from which relatively small quantities of water may be drawn for successive discharges as above indicated, the discharges being effected by novel means including a piston and cylinder and a storage tank, no valving means whatever being required between the cylinder and the tank, and the entire mechanism incorporating only a single valve, which is so arranged as to close the discharge orifice of the cylinder at all times except while the trigger is actually being pulled.

Another object of the invention is to provide such a toy water gun so constructed that although the external casing, preferably formed to simulate a hand weapon, may be economically stamped of light gauge sheet steel, those of the internal parts which are contacted by water are formed of non-rusting materials such as inexpensive molded plastic, the plastic components and other internal elements being properly positioned within the casing by the interfitted configuration of these parts and of the portions of the casing with which they engage so that no special holding means is required to maintain the proper relative positioning of the working parts.

Still another object is to provide a water-discharging toy having novel means for drawing successive charges of water from a storage tank to a discharge cylinder and for effecting discharge of the individual charges upon actuation of a trigger.

Other objects and advantages will be apparent upon consideration of the present disclosure in its entirety.

In the drawing:

Fig. 1 is a view principally in substantially central longitudinal section of a toy water pistol constructed in accordance with the present invention, certain internal portions being shown in side elevation;

Fig. 2 is a vertical sectional view taken sub-

2

stantially on the line 2—2 of Fig. 1 and looking in the direction of the arrows;

Fig. 3 is a view similar to Fig. 1 showing only the front portions of the gun and with the operating parts in a different position; and

Fig. 4 is a sectional detail taken substantially on the line 4—4 of Fig. 1 and looking in the direction of the arrows.

Referring now to the drawing, reference character 10 designates generally a casing indicated as formed of sheet metal and which may, as shown, be contoured to simulate a hand weapon or an imaginary or "futuristic" version of such a weapon. The casing is interiorly hollow, and 15 includes a hand grip portion 12 adjacent which is a trigger 14 projecting upwardly into and pivoted within the casing as upon a transverse pin 15. The casing may also include a forward portion 16 contoured to generally simulate a barrel, and a rearwardly extending overhanding portion 18 contoured to simulate generally the portion of an automatic weapon which carries the slide and other related parts. The portion 18 serves as a housing for a water tank 20, which 20 also projects over and partially into the hand grip 12. The water tank may be formed of molded plastic and provided with a filler opening 22 having a neck portion 24 which extends upwardly through an opening 25 in the top of the casing. If desired, the tank may also carry an upwardly extending finlike member 26 formed of colored plastic or other ornamental material adapted to project above the casing through an opening 28 and serving as an ornamental representation of a back sight. The sight portion 26 and filler neck 24 will be seen to provide interlocking engagement with the casing tending to prevent dislodgment of the tank, downward movement of the tank within the gun being prevented by the fact that the tank projects into the rear portion 18 of the casing.

An integral nipple 30 extends forwardly from a lower portion of the tank within the casing and a tube formed of rubber or other suitable 45 material and designated 32 is fitted upon the nipple and extends forwardly to a second nipple 34 projecting downwardly and rearwardly from a cylinder 35 mounted in the forward extremity of the barrel portion 16. The cylinder 35 is open at its rear end, arranged upon an axis substantially parallel with respect to that of the barrel portion, and is provided with a centrally disposed front opening 36. Cylinder 35 may also be formed of plastic material, and the passage 55 38 which extends through the nipple 34 opens

into the interior of the cylinder at a point substantially midway of the length thereof, defining a water-inlet port 33. The forward extremity of the barrel portion 16 is contoured to fit the exterior of the cylinder snugly, the cylinder engaging portion thus defined comprising a reduced cylindrical section 17 of the casing. The nipple 34, projecting downwardly behind the reduced section 17, positively locks the cylinder 35 against forward movement.

A muzzle cap 40 is fitted upon and projects forwardly from the cylinder 35 having a rearwardly extending cylindrical flange portion 42 which overlies and is rigidly attached to the front extremity of the cylinder 35, to which it may be secured by cement. The rear end of the flange 42 abuts the forward extremity of the reduced muzzle portion 17 of the barrel, so that when the sections 35, 40 are secured together they are positively locked against rearward movement by engagement between flange 42 and reduced muzzle portion 17. The portion of muzzle cap 40 which extends forwardly from the flange 42 is reduced to provide a shoulder 44 which partly overlies the front end of cylinder 35.

The rim portion 47 of a flat washer-like resilient valve member 45 is retained between shoulder 44 and the front of the cylinder 35. A flap valve portion 49 which is integral with the rim portion 47 which is defined by a cut-out area 48 comprising an incomplete circle which so separates the central valve portion 46 from the rim portion 47 that the central valve portion 46 is in effect hinged by the integral neck 53 constituted by the portion of the valve disk which is not cut out. The valve disk assembly thus formed may be comprised of resilient material such as rubber, and it will be noted that the diameter of the valve portion 46 is somewhat less than the internal diameter of the cylindrical opening 41 in muzzle cap 40. Opening 41 is coaxial with the cylinder 35. The valve portion 49 is urged against the head of the cylinder 35, to seal the opening 36, by a helical compression spring 52 housed within the chamber 41 in muzzle cap 40 and reacting at its forward end against the front wall of the cap, which is centrally pierced by a small hole 54 which determines the diameter of the water jet.

A piston 55 is reciprocable within the cylinder 35 and may be of double cupped configuration as shown and actuatable by means of a rod 56 secured to the piston and projecting rearwardly therefrom substantially axially through the barrel portion of the casing. The piston may be formed in one piece of rubber or rubber-like material as shown. The rear extremity of the rod 56 is bent laterally as indicated at 57, such laterally bent portion engaging within an opening 58 in trigger arm 60, and pivotal connection being thereby provided between the rod 55 and the arm 60, which will be seen to form an integral upward continuation of the trigger 14 lying within the casing.

A torsion spring 62 wrapped about the trigger pin 15 has one arm 63 reacting against the trigger arm 60 to urge it and the connected piston 55 rearwardly, the other arm 64 of the spring reacting downwardly against the bottom of the casing.

The trigger 14 and trigger arm 60 may comprise a unitary member of channel section. This part may be folded from a strip of sheet metal which is preliminarily pierced as indicated at 65, the pierced opening being formed in the portion of the sheet which becomes the bight of the sub-

sequently folded channel. The side webs of the channel-sectioned trigger and trigger arm assembly are also formed outwardly upon either side of the pierced area to enlarge the opening, and the tube 32 extends through such opening without interfering with free movement of the trigger and arm.

It is believed that the operation of the gun will be apparent from the foregoing, but it may be briefly summarized as follows: When the trigger is pulled, the initial forward movement of the piston 55 closes off the water inlet port 33, trapping in the cylinder the water which has previously flowed thereto. Continued forward movement of the piston drives the water out through the opening 36, valve portion 46 being forced open as indicated in Fig. 3 and the water being thereby ejected through the hole 54. When the trigger is released to permit the piston to return to the position shown in Fig. 1, the valve portion 46 closes immediately as the piston starts back, and rearward movement of the piston accordingly reduces the pressure within cylinder 35 below atmospheric, so that as soon as the front skirt of the piston clears the port 53, a quantity of water rushes into the cylinder to tend to equalize the pressure differential thus created between the cylinder and the tank 20.

It will be seen that if the gun is held approximately horizontal or with the muzzle pointed downwardly, which are the most common positions in which the pistol would be carried and held by the user, the hydrostatic head tends to keep the cylinder 35 full, although it will also be appreciated that since there is no inlet for air into the cylinder, the water will remain trapped therein for a long period of time in any event, ready for discharge upon the subsequent actuation of the trigger in the manner previously described.

It will be apparent that various modifications and changes may be made without departing from the fair and intended scope of the subjoined claims.

We claim:

1. In a liquid discharging gun construction, a hollow casing having a barrel portion terminating in a muzzle, a hand grip portion, and a hollow casing section overlying said hand grip portion, a liquid storage tank housed at least partly within said hollow casing section, a cylinder located within said barrel portion adjacent to the muzzle, a piston reciprocable within the cylinder, a trigger movably carried by the casing, a piston-actuating arm within the casing actuatable by the trigger, a liquid conduit connecting the tank to the cylinder, a portion of said tank being interfitting with said casing to retain the tank against movement in one direction, and a filler portion carried by said tank projecting through and from said casing and restraining said tank against movement in another direction with respect to the casing.

2. In a liquid discharging gun construction, a hollow casing having a barrel portion terminating in a muzzle, a hand grip portion, and a hollow casing section overlying said hand grip portion, a liquid storage tank housed at least partly within the hollow casing section, a cylinder located within said barrel portion adjacent to the muzzle, arranged substantially parallel to the barrel and having an opening facing rearwardly with respect thereto, a piston reciprocable within the cylinder, a trigger pivoted in said casing and projecting downwardly therefrom adjacent the

hand grip portion, such trigger having an arm projecting upwardly into the casing between said tank and cylinder, a liquid conduit connecting the tank to the cylinder, link means extending longitudinally through said barrel portion and connecting said arm to said piston, the outer end of said cylinder projecting beyond the muzzle portion and being provided with an outlet opening, check valve means normally closing said outlet opening but adapted to be opened by pressure within the cylinder, and a muzzle cap portion secured to the projecting portion of said cylinder and enclosing said valve and provided with a discharge orifice.
